CLAIM

The ornamental design for the one touch cap for fixing control cable, as shown and described.

DESCRIPTION

FIG. 1 is a plan view of a one touch cap for fixing a control cable, showing the new design;

FIG. 2 is a front view of the one touch cap for fixing a control cable;

FIG. 3 is a right side view of the one touch cap for fixing a control cable;

FIG. 4 is a bottom view of the one touch cap for fixing a control cable;

FIG. 5 is a back view of the one touch cap for fixing a control cable;

FIG. 6 is a left side view of the one touch cap for fixing a control cable;

FIG. 7 is a perspective view of the one touch cap for fixing a control cable; and,

FIG. 8 is another perspective view of the one touch cap for fixing a control cable.

In the drawings, the broken line disclosure in the drawing views forms no part of the claimed design.
